UNITED STATES PATENT OFFICE.

HENRY M. CASE, OF SYRACUSE, NEW YORK.

FUNNEL.

1,110,670.

Specification of Letters Patent. Patented Sept. 15, 1914.

Application filed September 12, 1912. Serial No. 720,050.

To all whom it may concern:

Be it known that I, HENRY M. CASE, a citizen of the United States, residing at Syracuse, in the county of Onondaga and State of New York, have invented certain new and useful Improvements in Funnels; and I do declare the following to be a full, clear, and exact description of the invention, such as will enable others skilled in the art 10 to which it appertains to make and use the same.

This invention relates to packaging liquids, and more especially to funnels; and the object of the same is to produce a gravity 15 valve in the bottom of a funnel and carried wholly by the nipple and nozzle thereof, so that when the latter is raised as in the act of pouring liquid into the neck of a bottle, the valve will be opened.

20 A further object is to produce a device of this kind wherein there are no exposed parts to become gummed or rusted by the liquid used, and wherein all parts can be readily detached as for the purpose of cleaning or repair.

25 These objects are accomplished by constructing the funnel and valve in the manner hereinafter more fully described and claimed and as shown in the drawings 30 wherein—

Figure 1 is a side elevation of a funnel embodying my invention, and Fig. 2 is a plan view thereof. Fig. 3 is a central vertical sectional view showing my improved 35 valve as opened by the automatic lifting of the spout or nozzle of a funnel as the latter is used in conjunction with a bottle which is shown in dotted lines. Figs. 4 and 5 are cross sections on the lines 4—4 and 5—5 of 40 Fig. 3.

The body F of this funnel may be of any suitable shape, and by preference it has a handle H and internally a strainer S which may be rendered removable by having a spring 45 wire W secured across the bottom of the strainer and engaged at its ends under lugs L formed in the inner wall of the body, so that the strainer can be put in place and turned to lock it there, or can be 50 turned and lifted out of place for cleaning the parts. The novelty in the present case resides more particularly in the form of gravity valve which I employ for automatically closing the outlet 55 nipple 1 of the funnel in a manner yet to be described. This nipple I would make

rather thicker than usual, and perhaps it might be a casting having its bore internally beveled at its upper corner as at 2 to form a valve seat, the entire casting being 60 secured within the lower end of the body F by any suitable means, and its upper end having a shoulder 1' around it while otherwise its interior is smooth and cylindrical. The spout or nozzle 3 I would by preference 65 make rather heavy, and I would give its exterior some considerable taper, especially at its lower end so that it may be inserted into the mouth of a bottle or other receptacle to be filled, and at some point said 70 mouth will bind on the exterior of the spout and push the latter upward for a purpose to appear below. Internally I form within said spout or nozzle a spider 4 standing at some distance below its upper end, and the 75 latter is made strictly cylindrical on its interior as at 5 so as to fit slidably around the outlet end or nipple 1 which depends from the body of the funnel. Screwed into the center of said spider as at 10 is the lower 80 member 11 of the valve itself, this member preferably having a surrounding shoulder 12 which rests upon the spider when the member is screwed tightly into place. The upper end of this member is cylindrical and extends 85 into the tubular lower end 13 of the upper member 14, being loosely held therein by a cross pin 15 so that the upper member may swing from side to side, and said pin passes through an aperture 16 made a trifle loose 90 on the pin so that the upper member may swing or flex in the opposite direction and in fact in all directions as will be clear. The upper member 14 externally of a size somewhat smaller than the bore of the nipple 1, 95 through which it projects, and its upper extremity is formed into a head 17 beveled around its edge as to fit closely on the valve seat 2 and preferably provided with a nick or kerf 18 across its top by means of which a screw driver may be engaged therewith.

Attention is directed to the fact that the length of parts is such that when the upper end of the spout 3 contacts with the shoulder 1' of the nipple, the lower end of the latter 105 is out of contact with the spider 4, and when the lower member 11 is screwed into the spider until its shoulder 12 is pressed thereon the head 17 of the upper member 14 is raised off the valve seat 2—all as shown 110 in Fig. 3. At this time, when liquid is flowing through the device as described be-

low, it is quite clear that the upper member 14 may fall to either side as it is loose within the bore of the nipple and it is loosely connected to the lower member so that it 5 may flex in all directions; and in order to center this member within such bore, when the parts assume the opposite position, the head 17 is beveled on its under side and the seat 2 is beveled correspondingly.

10 By connecting the two sections of the valve by a socket in the manner shown and described the hinged connected ends thereof will be properly covered and protected from the liquid or other contents within the funnel when drawn therefrom, whereby the upper section will always remain operative.

The parts are assembled as best seen in Fig. 1, and the weight of the spout or nozzle will cause it to slip downward on the 20 nipple 1, drawing with it the valve whose head of course is seated upon the valve seat in the manner therein shown. When now it is desired to use this funnel, the spout is inserted into a bottle-neck or other small 25 orifice until the same binds the exterior of the spout and raises the latter. With it moves the valve, whose head is therefore lifted off the valve seat, and, the valve being opened, liquid flows from the interior of the 30 body around said head, through the nipple and throughout the length of the spout, and into the vessel or other receptacle being filled. When sufficient has flowed therein, it is only necessary for the operator to raise 35 this funnel by lifting on its handle, and as the body ascends the valve seat strikes under the valve head and the latter is lifted and with it comes the valve stem and the entire nozzle. It will be obvious that the combined weight of the valve, spider, and spout 40 or nozzle, causes the head of the valve to close accurately against the valve seat; in addition to which there is the weight of the liquid contained within the funnel body 45 bearing downward on said head as will be clear. It is quite possible that the exterior of the spout could be made of other configuration than tapering as shown, and it could even have projections so that they 50 could be engaged with the edge of some large receptacle into which the liquid is to be drawn from the funnel. The obvious purpose of the loose pivot between the two members of the valve stem is in order to 55 prevent the valve head from unseating from the valve seat, even when the parts are canted out of a strictly vertical line. The purpose of having the lower end of the upper member completely inclose the upper 60 end of the lower member, is in order to prevent the accumulation of liquid in the loose pivot, which might rust the same or gum in place, or might have its effect upon some

other liquid passed through the funnel later. In order to separate the parts as for cleansing or repair, it is only necessary to engage a screw driver in the nick in the upper end of the head of the valve, and then rotate the spout to the left; this motion withdraws the threaded opening in the spider from the screw threaded lower end of the lower member of the valve stem, and the latter can then be entirely removed upward from the funnel body while the spout is drawn downward. When restoring the parts to the position shown in Fig. 3, this nick can be used in a reverse manner and the shoulder 12 becomes useful for preventing the movable valve stem from being screwed too far into the spider so that the valve head would not 80 work well on its seat. All parts can then be boiled or otherwise cleansed and restored; and on rare occasions if repairs are necessary, they can be made at this time.

I do not wish to be limited to the materials or sizes of parts, and changes in the details of construction may be made without departing from the principle of my invention.

What is claimed as new is:

The herein described self closing funnel comprising a cylindrical nipple having at its top an annular flange formed with a cone-shaped valve seat, a funnel body attached to said flange, a movable spout having a 95 tapered lower end to seat in the neck of a bottle and a cylindrical upper end to receive and slide on said nipple, a cross bar fixed in the intermediate portion of the spout and having a centrally arranged screw threaded 100 opening, a cone-shaped valve to engage said seat and formed on its bottom with a cylindrical stem of less diameter than the nipple, the lower end of said stem having a cylindrical socket, a plug having a shouldered 105 enlargement between its ends and a lower externally threaded end to screw into the opening in said cross bar, the upper end of said plug being formed with a longitudinally extending slot and being cylindrical and of less size than the socket in 110 said valve stem into which latter it projects, and a pin passed transversely through the lower end of the stem and the slot in said plug, said pin being of less diameter than 115 the width of the slot in said plug, substantially as shown and for the purpose set forth.

In testimony whereof I have hereunto set my hand in presence of two subscribing witnesses.

HENRY M. CASE.
